(57) CLAIM

The ornamental design for a sanitary napkin having an intergluteal strip, substantially as shown and described.

DESCRIPTION

FIG. 1 is a top plan view of a sanitary napkin having an intergluteal strip showing my new design.

FIG. 2 is a side view of the design in FIG. 1.

FIG. 3 is an end view from a first end of the design in FIG. 1.

FIG. 4 is an end view from a second end that is opposite the first end of the design in FIG. 1.

FIG. 5 is a bottom plan view of the design in FIG. 1.

FIG. 6 is a perspective view of the design in FIG. 1.

FIG. 7 is a top plan view of a first variant of a sanitary napkin showing my new design.

FIG. 8 is a side view of the design in FIG. 7.

FIG. 9 is an end view from a first end of the design in FIG. 7.

FIG. 10 is an end view from a second end that is opposite the first end of the design in FIG. 7.

FIG. 11 is a bottom plan view of the design in FIG. 7; and, FIG. 12 is a perspective view of the design in FIG. 7.
